US0D1031685S

(12) **United States Design Patent** (10) Patent No.: **US D1,031,685 S**
(45) Date of Patent: ** Jun. 18, 2024

(54) **ELECTRONIC DEVICE**

(71) Applicant: **Samsung Electronics Co., Ltd.**, Suwon-si (KR)

(72) Inventors: **Jun-Yong Song**, Suwon-si (KR); **Byoung-Jin Kim**, Suwon-si (KR); **Jung-Hyun Choi**, Suwon-si (KR); **Woo-Hyeok Jeong**, Suwon-si (KR); **Eun-Soo Kim**, Suwon-si (KR)

(73) Assignee: **SAMSUNG ELECTRONICS CO., LTD.**, Suwon-si (KR)

(**) Term: **15 Years**

(21) Appl. No.: **29/918,325**

(22) Filed: **Nov. 27, 2023**

Related U.S. Application Data

(63) Continuation of application No. 29/839,962, filed on May 25, 2022, which is a continuation of application (Continued)

CLAIM

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines in the figures illustrate portions of the electronic device that form no part of the claimed design.
